R. G. HAMAKER

SUPPORT

Filed June 1, 1925

Rex G. Hamaker Inventor

By *Jesse R. Stone*

Attorney

UNITED STATES PATENT OFFICE.

REX G. HAMAKER, OF HOUSTON, TEXAS, ASSIGNOR OF ONE-HALF TO A. M. BOWMAN,
OF HOUSTON, TEXAS.

SUPPORT.

Application filed June 1, 1925. Serial No. 34,075.

My invention relates to a Samson post construction for use on standard rigs employed in drilling or pumping oil wells.

In the type of Samson post now ordinarily employed on standard rigs, the post comprises a single upright support which may be braced on its forward and rear sides by ordinary tie rods. The walking beam is pivoted for oscillation upon the upper end of said post. When the stroke of the walking beam is long, so that the ends of the said beam oscillate through a large arc, the strain upon the post becomes great, and the braces now employed do not effectively withstand the same. As a result, the post becomes unsteady and does not maintain its proper alignment for very long.

It is an object of my invention to provide a walking beam support which will present an effective resistance to the strain exerted thereon by the movement of the beam. It is desired that the structure be strong and simple in construction and readily installed and secured in position.

In the drawing is illustrated the preferred embodiment of the invention, the frame, or support, being shown in side elevation.

The support which I have devised to take the place of the ordinary Samson post comprises two legs 1, which may be of structural steel, preferably of I-beam construction. Said legs are secured together at their upper ends, and are inclined apart at their lower ends, forming an inverted V in shape. The lower ends are secured to plates 2, extending laterally from the said legs and adapted to be secured to a base by means of bolts or screws indicated at 3.

The upper ends of the legs are secured together by plates 4, bolted to the legs. A bearing block 5, which is bolted to the plates 4, has on its upper end a bearing groove to receive the pivot shaft, or trunnion, 6 secured to a block 7 on the lower side of the walking beam 8. The trunnion is held in the bearing by plates 9 on the bearing block at each side of the walking beam.

The walking beam is rocked on its pivot by the usual pitman 10, secured through a yoke 11 to the beam at its upper end, and to the crank pin 12 at its lower end. Said crank pin is mounted on the crank arm 13, formed on the shaft 14 of the band wheel 15, said shaft be-

ing mounted in bearings supported upon the jack posts 16.

The legs of the Samson post frame must withstand heavy strains exerted in the plane of the walking beam. This strain, exerted downwardly, tends to spread the legs of the support, and to overcome this strain, and strengthen the structure, I provide a supporting rod 17 in two sections, the outer ends of which are bolted to the lower ends of the legs at 18 and the adjacent ends of which are secured together by a turnbuckle 19. By means of this turnbuckle the rod acts as a tension member effectively preventing the legs from spreading. The rod, in effect, forms the third side of a triangular frame making up a structure of great strength, in which the lateral strain in the direction parallel to the base is sustained by the rod. This make of Samson post is particularly adapted to withstand the pull of the walking beam, and although simple in construction, it will serve its purpose for long periods without necessity of replacement or repair. The use of this support for the walking beam forms a combination which has been found to be a material improvement in the art.

What I claim as new and desire to protect by Letters Patent is:

1. A Samson post adapted to support a walking beam comprising a pair of legs of uniform width inclined together at their upper ends and adapted to resist strain in the vertical plane of said walking beam, a supporting plate securing said legs together at their upper ends, means to anchor said legs rigidly to a supporting base, and an adjustable tension member connecting said legs together adjacent the lower ends thereof.

2. A walking beam support comprising two legs of uniform width inclined together at their upper ends, a bearing block thereon, the lower ends of said legs being spaced apart in the plane of said walking beam, means to secure the said legs to a supporting base, and a rod connecting said legs adjacent their lower ends, said rod having tension means therein, whereby said legs are reinforced in the direction of the strain thereon.

In testimony whereof I hereunto affix my signature this 28th day of May, A. D. 1925.

REX G. HAMAKER.
